UNITED STATES PATENT OFFICE

2,562,916

DOOR FASTENER

Carl Edwin Hoffman, Allentown, Pa., assignor, by direct and mesne assignments, of one-half to Commonwealth of Pennsylvania, Department of Public Assistance and one-half to Edwin C. Hoffman, Allentown, Pa.

Application July 12, 1946, Serial No. 683,129

4 Claims. (Cl. 292—265)

1

My invention relates to improvements in door fasteners with particular reference to devices of this character which are adapted for locking a door in either a closed or a partly opened position, the present invention being an improvement over the device disclosed in my Patent #1,548,270, dated August 4, 1925.

The invention is characterized by a keeper and latch mounted on a door and jamb, and is adapted for locking the door in closed position, the latch being provided with an operating means adapted for association with the keeper to lock the door in partly open position.

One of the important objects of the invention, as hereinabove characterized, is to provide yielding retaining means for maintaining the latch in either its operative or inoperative position, whereby it will not be operated by the weight of the keeper engaging latch operator when the latter is disengaged from the keeper.

The further and more specific object of the invention is to provide in a door fastener a latch mounted on either the jamb or door for engaging a keeper to retain the door closed.

A still further and more specific object of the invention is to provide in a door fastener as characterized, a latch and attaching base which incorporates interfitting bearing members, one of said bearing members having end notches and the other bearing member providing a rib selectively engaging in said notches and yielding means tending to bring about engagement between said notches and rib whereby the weight of a keeper engaging latch carried operator will be prevented from releasing the latch when it is employed to keep the door closed.

Another object of the invention is to provide a device of this kind which is very simple in construction, easy to operate besides being relatively inexpensive to manufacture.

Other objects and advantages of the invention will be apparent to those skilled in the art as the description proceeds, reference being had to the accompanying drawings illustrating the now preferred example of the invention.

It will be understood, however, that the invention is susceptible of other mechanical expressions within the spirit and scope of the subject matter claimed hereinafter.

In the drawings, wherein the same reference characters have been used to designate the same parts in all views—

Fig. 1 is a perspective view of the device applied to an inwardly opening door and its associated jamb, with the latch positioned to retain the door fully closed;

2

Fig. 2 is a view similar to Fig. 1, but showing the device arranged for retaining the door partly open;

Fig. 3 is a vertical view through the novel latch element, per se, as shown in Fig. 1;

Fig. 4 is a horizontal sectional view through the latch, per se, as shown in Fig. 1;

Fig. 5 is a plan view of the rotatable latch element removed, and looking into the inner base plate-carried end thereof; and

Fig. 6 is a perspective view of the jamb-carried base plate and showing the sleeve end notches 23a for selectively engaging the rivet 20 of rotatable latch 12.

Referring to the drawings by reference characters, the numeral 8 designates an inwardly opening door and 9 indicates the jamb.

The door fastener, which is the subject of the instant invention, comprises a latch-carrying base plate 10, which is adapted to be secured to either a door or a door jamb by means of screws or the like 11. In the case of an inwardly opening door, the latch-carrying plate 10 will be secured to the jamb 9, for reasons which will be apparent hereinafter.

The latch 12, which is pivoted to base plate 10, is illustrated as a rectangular bar-like member having a latch portion 12a at one end, the back of the latch having an outwardly extending boss 13. The outer end of the boss 13 terminates in the bifurcation providing the spaced ears 13a, which are transversely apertured as at 13b.

A combined latch-operating and keeper-engaging lever 14 has its inner end pivoted on pin 13c, between the ears 13a. The outer end of the lever 14 has the reverted keeper engaging portion 14d, which is spaced laterally from the major lever portion and whose edges are provided with a series of spaced transverse notches 15 for selective engagement with the lower leg portion of the door-carried keeper 16, to retain the door partly open, as shown. Keeper 16 is secured to the mounting plate 17, which is fastened to the jamb-engaging end of door 9.

The lever carrying boss 13, of the latch 12, is provided with a deep cylindrical bearing recess 18, extending inwardly from the base plate engaging face of said latch 12. This bearing recess 18 is adapted to receive the base plate-carried sleeve 22, for pivoting latch 12, to the base plate 10.

Extending outwardly from the recess 18 is the concentrically located pin 19. As shown in the drawing, the inner end of the pin 19 seats in a counter-bore 18a, and it functions not only as a supplementary latch bearing element, but also

as a part of a latch and plate retaining and latch position control means, all as will be presently understood.

This pin 19 is retained in place by means of the transverse rivet 20 whose ends seat in the opposite wall portions of the boss 13. The rivet, as intimated, goes through the pin 19, and it is important to note that about half the diameter of the rivet 20 protrudes as a ridge beyond the inner end surface of the recess 18. The advantage of this last mentioned particular arrangement will be emphasized hereinafter.

The drawing also shows that the latch carried pin 19 extends outwardly from the inner face of the latch 12 a distance approximating the thickness of the base plate 10, the outer end of said pin extending beyond relatively deep opposed bottom surface recess 25 in base plate 10. This bottom surface recess 25 of base plate 10 seats opposite ends of a cotter pin or the like, 24, which is extended through a transverse hole in latch-carried pin 19. The purpose of this is to retain the parts assembled, as will be better understood later.

The base plate 10 has a bearing opening 21 concentric with and somewhat smaller than latch boss opening 18, and through which the latch carried pin 19 concentrically extends. Surrounding, or sweated into the latch base opening 21, is the integral or rigidly attached bearing sleeve 22, previously referred to, as adapted for reception in the latch provided bearing recess 18, with which it makes a relatively stable bearing fit.

The outer end of the base plate carried sleeve 22 has an inwardly extending flange 23 defining, concentric with the base plate opening 21, a bearing for the latch carried pin 19. Thus, in effect there is provided a double bearing connection between the latch 12 and its base plate 10. One of these latch bearings is obviously provided by the interfitting sleeve and recess portions 22, 18. The other latch bearing is furnished by the latch carried pin 19 and its bearing engagement in the hole provided flange 23 of the base-carried sleeve portion 23 (see Figs. 3 and 4); and second, by the bearing engagement of pin 19 in a washer 27 seated in the opening 21 of base plate 10 (see Figs. 3 and 4). This double bearing is, as will be appreciated, a very important feature when applied to an instrumentality such as a lock, where the provision of strength is of prime importance.

The outer end of the flange 23, of the base plate-carried sleeve 22, is provided with circumferentially spaced pairs of opposed notches 23a, adapted to selectively engage the raised or exposed rib-like portion of rivet 20 at the end of the latch-provided recess 18. In order to retain the latch 12 and base plate 10 assembled, the cotter pin 24, previously mentioned, is passed through a transverse hole in the bearing pin 19, outwardly of the washer 27, which is seated in plate recess 25.

Recess 25, as shown, is of a depth sufficient to dispose the cotter pin 24 inwardly of the plane of the inner surface of base plate 10. This enables base plate 10 to make flat contact with the door or jamb to which it is attached.

Although the cotter pin 24 holds the base plate and latch 12, 10 in assembly, it does permit of slight separating movement of the latch and its base plate against the action of the spring 26, to be dealt with presently. The permitted amount of this separating movement is approximately equal to the thickness of the exposed por-

tion of the rivet 20, so that the base plate carried sleeve and latch 12 may partake of sufficient relative movement to allow for engagement and disengagement of notches 23a from the cotter pin 20.

As illustrated, there is an annular space between the pin 19 and the base-carried sleeve 22. This space is occupied by a coil spring 26, incidentally mentioned hereinabove. One end of said spring 26 bears against the inwardly extending flange 23 of the base carried sleeve 22, while the other end bears against the inner surface of the washer 27. Thus, spring 26 normally acts through washer 27, cotter pin 24 and pin 18 to draw the latch 12 into flat contact with base plate 10, and likewise exposed rivet-provided rib 20 against the notched end 23, 23a of the plate-carried sleeve 22. Thus, the latch 12 will be yieldably retained in predetermined operative or inoperative position against accidental shifting, by engagement of selected pairs of notches with the rivet-provided rib 20.

Having thus described my invention, what I claim as new and desire to secure by Letters Patent is:

1. A door fastener of the class described comprising a latch, a base plate supporting said latch, interfitting spaced bearings carried by said base plate and latch for mounting the latch for swinging movement in a plane with the base plate, said bearing means including a transverse bore in the latch and an outwardly extending boss on the base plate mounted within said latch bore, a concentric pin extending outwardly from said bore, a transverse rivet extending through the latch and pin for retaining the latter in place, a portion of said rivet projecting outwardly of the plane of the end of said bore to provide a rib, and the base plate-carried bearing portion comprising a sleeve having end notches selectively engageable with said exposed rib-providing rivet portion, and a coil spring tending to bring the notched end of said sleeve into engagement with said rivet provided rib whereby to yieldably retain the latch against movement relatively of its base plate.

2. A door fastener of the class described comprising a swingably mounted latch and keeper adapted for interchangeable mounting on a door and associated jamb, a mounting plate for said latch, means associated with the mounting plate and latch for rotatably securing the latch to the mounting plate, and inter-engageable means carried by the mounting plate and latch adapted to retain the latter in keeper or non-keeper engaging position, spring means associated with said latch and latch mounting plate for positioning said inter-engageable means for engagement with one another when the latch is swung, an operating lever for said latch and pivoted thereto, said lever having a reversely bent terminal portion paralleling its major portion, said keeper providing a loop, and said reversely bent latch portion having notches, the reversely bent latch portion being adapted to be received in the keeper loop when the door is opened and the latch released from the keeper.

3. A door fastener of the class described comprising a swingably mounted latch consisting of a body of substantial thickness, said latch body having a substantially central cylindrical bore extending outwardly from its inner surface, said bore terminating short of the outer surface of said latch body, a latch supporting plate adapted for mounting on the exterior surface of a door

jamb, said latch supporting plate having an outwardly extending sleeve slightly smaller diametrically than said latch bore and extending into the latter whereby to pivotally mount the latch body for movement relatively of the latch supporting plate, the bore of said latch body having a concentric counter-bore, a stud seated in the counter-bore of said latch body, said stud extending into and being spaced concentrically from the inner surface of said sleeve, the outer end of said sleeve within the bore of said latch body having circumferentially spaced opposed pairs of end notches, a transverse pin extending through said latch body and stud for securing the same together, portions of said stud-securing pin being exposed inwardly of the plane of the inner end of the latch body bore at opposite sides of said stud, said exposed portion of said stud-securing pin being adapted to be selectively received in said pairs of said notches in the outer end of said latch supporting plate carried sleeve, the outer end of said sleeve having an inwardly extending circumferential-flange providing a bearing for the inner end of said latch body-carried stud, a coil spring surrounding said stud and bearing against said sleeve flange, said latch body-carried stud extending substantially to the plane of said latch supporting plate, and a stop on said

stud adjacent said latch supporting plate and providing a bearing for the other end of said coil spring whereby said coil spring normally urges the exposed portion of said stud securing pin against the proximate end of said plate carried sleeve.

4. The combination set forth in claim 3, and an operating lever for said latch and tending by its weight to swing the latch in an opening direction but retained against doing so by the engagement of said pin in one of said pairs of end notches of the sleeve of said latch-supporting plate, and others of said sleeve notches being adapted to engage said stud securing pin when the latch is open to retain said lever against shifting and said lever in said latter position being adapted to engage a keeper element for maintaining a door partly open.
